C. E. DAVIS

DRAFT DEVICE FOR MINING MACHINES

Filed May 6, 1920

Patented May 5, 1925.

1,536,795

UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

DRAFT DEVICE FOR MINING MACHINES.

Application filed May 6, 1920. Serial No. 379,237.

To all whom it may concern:

Be it known that I, CHARLES E. DAVIS, a citizen of the United States, residing at Chicago, in the county of Cook and State of Illinois, have invented a Draft Device for Mining Machines, of which the following is a specification.

This invention relates to improvements in draft devices for coal mining machines of the class adapted to be moved along the face of the mine wall to cut a horizontal kerf thereunder, and has for its principal object to provide a means associated with the draft mechanism for controlling the height of the kerf.

My invention will be best understood by reference to the accompanying drawings in which Figure 1 is a plan view of a mining machine provided with a mechanism embodying my invention.

Figure 2 is a side view of a mining machine.

Figure 3 is a detailed view of my invention as applied to the pulley or feed rope of the mining machine.

Figure 4 is a cross-section view taken on line 4—4 of Figure 3.

Figure 5 is a view of the rear end of the mining machine showing a modification of my invention as applied to the retarding or tail rope.

Figure 6 is a vertical cross-section taken on line 6—6 of Figure 5.

Figure 7 is a horizontal cross-section taken on line 7—7 of Figure 5.

Mining machines of the class shown herein to illustrate my invention, have as a common feature a body portion A adapted to rest on the mine floor, and a cutter bar B extending horizontally from the frame and carrying a movable cutter chain of any approved construction as indicated by dotted lines in Figure 1. Such machines are provided with a motor suitably mounted on the frame A and having driving connection with the cutter chain, and also having driving connection with a suitable draft device for moving the machine during its cutting operation. In the machine illustrated, a draft device comprises a cable drum 1 driven by the motor and carrying a flexible cable 2 called the feed rope, adapted to be anchored at a distance from the machine. A second draft device is also provided for retarding the rear end of the machine frame and maintaining the desired angular relation of the machine to the mine wall as it moves therealong during the cutting operation. This second draft device may comprise a cable drum 3 provided with a suitable friction device 4 and carrying a cable 5, usually termed the tail rope.

In the operation of machines of the class above described, it is often necessary to follow the rolling or undulating mine floor in forming the kerf, and while so doing, the cutter bar B has a natural tendency to travel in a horizontal plane predetermined by its position when its initial cut is made under the coal. Furthermore, it sometimes occurs that the cutter bar becomes deflected upwardly from the mine floor as it moves laterally, which deflection may be due to several causes, as for instance, coming in contact with relatively hard material, or on account of uneven degree of sharpness of the cutter bits which make up the cutter chain. One device heretofore used for the purpose of correcting this fault, has been an adjustable tilting shoe forming a portion of the bottom face of the body portion on which the machine rests. However, such a tilting shoe has certain disadvantages, as for instance, it interferes with the movement and operation of the machine, it is relatively difficult to adjust the height on account of the weight carried thereby, and in machines which are particularly desirable for work in extreme low veins of coal, it has been impractical to include such a tilting shoe in the construction of the machine on account of the limited headspace available. In the present invention, I provide means for controlling the lateral movement of the cutter bar by means of a novel arrangement of the draft device. One embodiment of my invention is illustrated in Figures 1 and 2, and comprises a horizontally disposed sheave 6 with which the feed rope 2 is adapted to be engaged. This sheave has heretofore been similarly positioned on machines of this class, but has been fixed in a position substantially in the horizontal plane of movement of the cutter chain about the cutter bar B, that is to say, in the position occupied by the sheave in Figure 2. In the present invention, I provide means of adjusting this sheave vertically, which means comprises a vertically disposed screw shaft 7 threaded as shown, and mounted at its upper and

2
 lower ends in suitable brackets 8 and 9. A sleeve 10 is threaded by said shaft and provides a bearing for the sheave 6. A guide 11 is carried by the sleeve 10, and extends laterally from under the sheave to engage the side wall 11^a of the machine. This guide serves to retain the rope 2 in engaging position with the sheave when the rope is slack, and also restrains the sleeve 10 against turning on the shaft 7. A washer 12 may be provided for the top of the sleeve 10 so as to allow the sheave to be removed therefrom if desired. The shaft 7 may be turned by means of a wrench or similar device applied to the flattened end portion 13 of the shaft 7 extending upwardly and beyond the bracket 8, as shown. I have found that by means of an adjustment of a few inches in the height of the sheave 6, the movement of the cutter bar may be deflected either upwardly or downwardly, as desired.

In another arrangement shown in Figures 5, 6 and 7, my invention is shown as applied to the tail rope 5, at the rear end of the machine. It is obvious that it is not necessary to provide a machine with a controlling device on both the feed and the tail ropes, but both arrangements are illustrated herein to show various ways in which my invention may be applied. The second arrangement may comprise a vertically disposed shaft 14 having bearings at its upper and lower ends in suitable brackets 15 and 16 respectively, and provided with hand wheel 17 at its upper end, if desired. A sheave 18 is mounted on a stud 19 carried by a vertically movable block 20 having threaded engagement with the shaft 14, and retained in a dove tailed slot formed by vertically disposed guide members 21, 21, attached to the rear end of the mining machine A. When the tail rope is anchored in position to one side of the machine during the cutting operation, the rope 5 may be led directly to the anchor without engaging with the pulley 18. Theoretically, it is desirable to arrange the tail rope drum 3 so that the tail rope 5 is paved off at a point substantially in the same plane as the center line of the cutter bar B so as to balance the pull of the feed rope 2 in the opposite direction.

In order to provide a tipping movement to the machine in addition to that already described, the drum 3 and sheave 18 may be spaced on opposite sides of the machine, with the sheave 18 intermediate the anchor and drum, and on a line therewith, as shown. With this arrangement, it will be observed that when the rope 5 is placed under the pulley 18, the tension on the rope tends to lift the side of the machine nearest the anchor. It is obvious that the feed rope 2 might be similarly arranged, that is to say, the mechanism shown in Figure 5 might be

used with the feed rope, if desired. In the event that the cutter bar should assume an angular relation to the mine floor and start an upward cut, the rope 5 may then be led underneath the sheave 18, moved to a position adjacent the mine floor, thereby exerting a tipping movement to the machine frame owing to the tension on the rope 5.

Altho I have shown and described two forms in which my invention may be embodied, it will be understood that many other means may be employed for accomplishing the same results without departing from the spirit and scope of my invention. I do not therefor wish to be understood as limiting myself to the specific constructions illustrated herein excepting as specifically limited in the appended claims.

Having described my invention what I claim as new and desire to cover by Letters Patent, is:

1. The combination of a mining machine having an elongated frame movable bodily along the ground and provided with suitable cutting mechanism extending longitudinally from one end thereof, a flexible draft means adapted to be anchored at a distance from the machine and having normal connection with said machine at a predetermined vertical position adjacent one end of said frame, a guide on said machine having detachable engagement with said draft means intermediate the machine and draft anchor to deflect said draft means vertically from its normal point of connection with said machine, and other draft means connected adjacent the opposite end of said frame and adapted to extend and be anchored in the opposite direction from said first named draft means.

2. The combination of a mining machine having an elongated frame movable bodily along the ground, and provided with suitable cutting mechanism extending longitudinally from one end thereof, a flexible draft means adapted to be anchored at a distance from the machine and having normal connection with said machine at a predetermined vertical position adjacent one end of said frame, a guide on said machine having detachable engagement with said draft means intermediate the machine and draft anchor to deflect the same from its normal line, means for adjusting said guide vertically with respect to said cutting mechanism, and other draft means connected adjacent the opposite end of said frame and adapted to extend and be anchored in the opposite direction from said first named draft means.

3. The combination of a mining machine having suitable cutting mechanism for cutting a continuous kerf, a flexible draft means adapted to be anchored at a distance from the machine and having normal connection

with said machine substantially in horizontal alignment with said cutting mechanism, means affording vertical adjustment of said draft means on said machine, and other draft means connected in offset relation with said first named draft means and operable on the opposite end thereof to maintain the frame in the desired angular relation to the mine face.

- 10 4. In combination with a mining machine having suitable cutting mechanism for cutting a kerf, a flexible draft means adapted to be anchored at a distance from the machine, a guide for said draft device mounted 15 on a vertically disposed shaft, substantially in horizontal alignment with respect to said cutting mechanism, and means for adjusting

said guide along said shaft, above or below said cutting mechanism.

5. In combination with a mining machine 20 having suitable cutting mechanism for cutting a kerf, a flexible draft means adapted to be anchored at a distance from the machine, a guide for said draft means on said machine, substantially in alignment with 25 said cutting mechanism, and means for moving said guide above or below said cutting mechanism comprising a vertically disposed shaft, a bearing for said guide having threaded engagement with said shaft, and 30 means preventing the rotation of said bearing.

CHARLES E. DAVIS.
